UNITED STATES PATENT OFFICE.

JESSEE MELTON THOMAS, OF TAMPA, FLORIDA.

TRAVELING KIT.

Application filed September 22, 1923. Serial No. 664,257.

To all whom it may concern:

Be it known that I, JESSEE MELTON THOMAS, a citizen of the United States, and a resident of Tampa, in the county of Hillsborough and State of Florida, have invented 5 certain new and useful Improvements in Traveling Kits, of which the following is a specification.

This invention relates to traveling kits 10 especially adapted for use in connection with automobiles and other vehicles.

An important object of this invention is to provide a traveling kit which may be conveniently applied either to the running 15 board or rear of a vehicle and which may be readily opened for use as a table, or a bed and which is provided with a tent covering, a cook stove and a suitable number of chairs.

A further object is to provide a traveling 20 kit of the character specified which is convenient to operate, of highly simplified construction and which is cheap to manufacture.

Other objects and advantages will be apparent during the course of the following 25 description.

In the accompanying drawing forming a part of this application and in which like numerals are employed to designate like parts throughout the same,

30 Figure 1 is a perspective of the improved traveling kit in use as a table, the cook stove and the chairs also being shown in place.

Figure 2 is a perspective of the improved traveling kit positioned for use as a bed.

35 Figure 3 is a perspective of the improved kit partly opened.

Figure 4 is a perspective of the kit closed.

In the drawing wherein for the purpose 40 of illustration is shown a preferred embodiment of the invention the numeral 5 generally designates a container which when folded resembles a traveling case or trunk of the type carried in automobiles. The container 5 is provided at its lower end with 45 a pair of laterally projecting trunnions 6 mounted upon the heads of bolts or standards 7, the said standards being extended through base members 8. With reference to Figure 4 it will be observed that an adjusting nut 9 is mounted upon each standard 7 and forms a means whereby the height of the container may be varied. The base mem-

bers 8 may be applied to the running board 10 of the vehicle 12 or the container may be attached by means of brackets or other means 55 to the rear of the vehicle.

The container consists of a pair of similarly constructed sections 14 and 16, the side walls of which are adapted to have edge to edge engagement and it will be seen that 60 the section 14 is provided with the trunnions 6 and is therefore more or less permanently secured to the running board 10. However the inner section 14 may be positioned as illustrated in Figure 2 or as illustrated in Figure 1. 65

It will be observed with reference to Figure 3 that the side walls of the outer section 16 are hingedly connected as indicated at 18 to the side walls of the inner 70 section 14 so that the section 16 may be swung to any one of its possible positions.

A top section 20 is provided with a front wall 21 and with parallel end walls 22, the latter being hingedly connected to the back 75 of the inner or rear section 14. When the kit is folded the coating fastening devices on the front wall 21 of the top 20 engage the fastening devices 23 on the front wall of the outer section 16 so as to completely close 80 the kit. By reason of this construction no cracks are in the top of the kit and consequently rain and snow is effectively excluded. The complete closing of the top of the kit and the absence of a crack in the top 85 is thus made possible notwithstanding the fact that the inner and outer sections 14 and 16 respectively are horizontally hinged to each other at their upper ends.

It might be stated that when the sections 90 14 and 15 are positioned horizontally as illustrated in Fig. 1 the top 20 constitutes a hood for a cook stove 25.

A frame 30 is horizontally hinged to the lower portion of the inner section 14 and 95 consists of a pair of sections 31 and 32 pivotally connected at their inner ends as indicated at 33 so that the same may be conveniently collapsed.

Figure 3 illustrates that supporting legs 100 34 are connected to the sections 31 and 32 by means of links 36 and 37, the said links being pivotally connected to the side bars or rails of the sections of the frame. An

additional bracing link 38 is hingedly connected to each link as indicated at 39 and is connected to the adjacent side rail of the section 31 as indicated at 40. By moving 5 the adjacent portions of the sections 31 and 32 upwardly the frame may be collapsed and folded within the sections 14 and 15 and the legs 42 which support one end of the frame 30 may be swung into parallel relation to 10 the outer section 32 so that the frame when collapsed will occupy but a small amount of space. Suitable brace members 44 and 46 are secured to the legs 42 and the section 32 and provide a reliable means to connect the 15 legs to the section 32.

When the frame is positioned horizontally as illustrated in Figure 2 a mattress 50 is placed upon the springs 52 and the bowed member 54 is swung to its elevated position. 20 The member 54 is of U-shaped formation and has its sides provided with laterally projecting ears 56 which are pivotally connected to the side rails of the section 32. This permits the member 54 to be swung to 25 the collapsed position illustrated in Figure 3. The U-shaped member 54 may be secured to the braces or supports 46 by means of latches 57 which as illustrated in Figure 3 are pivotally connected to the lower portions 30 of the side members of the arch 54. Therefore the arch 54 cannot accidentally collapse when in use.

When not in use the kit is carried in the 35 position illustrated in Figure 4 and the sections 14 and 16 are held together by a fastening device 73 and are circled by a fastening strap 74. The strap 74 may also be employed as a means to secure the kit to the body of the vehicle or any other suitable 40 means may be employed.

Assuming it is desired to spend the night on the road, the frame 30 is horizontally positioned and the mattress 50 is mounted upon the frame as illustrated in Figure 2. 45 If desired, the canopy 78 may be attached to the top 80 of the vehicle and it may be extended over the arch 54. Suitable fastening ropes 83 may be employed for stretching the canopy and holding the same taut. The 50 ropes 83 may be staked to the ground or otherwise anchored.

If it is desired to set the kit up as a table, the sections 14 and 15 are horizontally positioned as illustrated in Figure 1 and the cook 55 stove 25 is positioned adjacent or partly within the hood 20. Suitable chairs 89 are arranged on opposite sides of the frame and may be carried in any desired manner.

The invention forming the subject matter 60 of this application may be very conveniently carried on a vehicle or may be set up within one's house. A single or double bed may be employed and it will be observed that the mattress may be located within the container when the kit is collapsed.

Having thus described the invention, what is claimed is:—

1. A traveling kit comprising a container consisting of a pair of similarly constructed sections having side walls, the edges of which are adapted for abutment, a hood horizontally hinged to one of said sections and adapted to extend over and close the upper ends of said sections, a frame horizontally hinged to the lower portion of one of said sections, legs connected to said sections, and an arched support horizontally hinged to one of the sections of said frame. 70 75

2. A traveling kit comprising a container having a pair of similar sections provided with side walls, the edges of which are adapted for engaging each other, a hood horizontally hinged to one of the sections and constituting a closure for the upper end of the sections, a frame horizontally hinged 80 to the lower portion of one of said sections and being collapsible, and means supporting one of said sections of said container for movement about a horizontal axis, said sections of the container constituting a table 85 when arranged horizontally upon said frame. 90

3. A traveling kit comprising a container having a pair of similar sections provided with side walls, the edges of which are 95 adapted for engaging each other, a hood horizontally hinged to one of the sections and constituting a closure for the upper end of the sections, a frame horizontally hinged 100 to the lower portion of one of said sections and being collapsible, means supporting one of said sections of said container for movement about a horizontal axis, said sections of the container constituting a table when 105 arranged horizontally upon said frame, and an arched support horizontally hinged to the outer portion of the frame and having means whereby the same may be secured in an upright position. 110

4. A traveling kit comprising a container having a pair of similar sections provided with side walls, the edges of which are adapted for engaging each other, a hood horizontally hinged to one of the sections and constituting a closure for the upper end 115 of the sections, a frame horizontally hinged to the lower portion of one of said sections and being collapsible, means supporting one of said sections of said container for movement about a horizontal axis, said sections 120 of the container constituting a table when arranged horizontally upon said frame, and legs for supporting said frame.

5. A traveling kit comprising a container having a pair of similar sections provided 125 with side walls, the edges of which are adapted for engaging each other, a hood horizontally hinged to one of the sections and constituting a closure for the upper end of the sections, a frame horizontally hinged

to the lower portion of one of the sections and being collapsible, means supporting one of said sections of said container for movement about a horizontal axis, said sections 5 of the container constituting a table when arranged horizontally upon said frame, an arched support horizontally hinged to the outer portion of the frame and having means whereby the same may be anchored in an 10 upright position, and a mattress adapted to be arranged upon said frame.

6. A traveling kit comprising a container having a pair of similar sections provided with side walls, a hood horizontally hinged 15 to one of the sections and constituting a closure for the upper end of the sections, a frame horizontally hinged to the lower portion of one of the sections and being collapsible, means supporting one of said sections of said container for movement about a horizontal axis, said sections of the container constituting a table when arranged horizontally upon said frame, and a mattress adapted to be arranged upon said 20 frame, said hood constituting a protector means for a cook stove.

7. A traveling kit comprising a container having a pair of sections, means supporting one of the sections for movement 30 about a horizontal axis, said sections being hingedly connected to each other and adapted to form a table when arranged horizontal-

ly, a frame for supporting said sections in a horizontal position, and legs for supporting said frame. 35

8. A traveling kit comprising a container having a pair of similar sections provided with side walls, the edges of which are adapted for engaging each other, a frame horizontally hinged to the lower portion of 40 one of the sections and being collapsible, means supporting one of said sections of said container for movement about a horizontal axis, said sections of the container constituting a table when arranged horizontally upon said frame, an arched support 45 horizontally hinged to the outer portion of the frame having means whereby the same may be anchored in an upright position, and a mattress adapted to be arranged upon said frame. 50

9. A traveling kit comprising a container having a pair of similar sections provided with side walls, a frame horizontally hinged to the lower portion of one of the sections 55 and being collapsible, means supporting one of said sections of said container for movement about a horizontal axis, said sections of the container constituting a table when arranged horizontally upon said frame, and 60 a mattress adapted to be arranged upon said frame.

JESSEE MELTON THOMAS.
